(57) **CLAIM**

The ornamental Design for a board to board plug connector, as shown and described.

DESCRIPTION

FIG. 1 is a top plan view of a board to board plug connector showing our new design;

FIG. 2 is a bottom plan view thereof;

FIG. 3 is a front elevational view thereof, the rear elevational view being a mirror image thereof;

FIG. 4 is a left side elevational view thereof, the right side elevational view being a mirror image thereof;

FIG. 5 is a top plan view of another embodiment of our new design, which is longer in length than the plan view of FIG. 1;

FIG. 6 is a bottom plan view of the second embodiment of FIG. 5; and,

FIG. 7 is a front elevational view of the embodiment of FIG. 5, the rear elevational view being a mirror image thereof.

The left and right end views of the embodiment of FIG. 5 are the same as FIG. 4.
